UNITED STATES PATENT OFFICE.

CHARLES L. THAYER, OF PLAINVILLE, KANSAS.

COMBINED SPARKING PLUG AND SPARK INTENSIFIER FOR INTERNAL-COMBUSTION ENGINES.

1,413,142.

Specification of Letters Patent. Patented Apr. 18, 1922.

Application filed October 27, 1920. Serial No. 419,948.

To all whom it may concern:

Be it known that I, CHARLES L. THAYER, a citizen of the United States, residing at Plainville, in the county of Rooks and State 5 of Kansas, have invented certain new and useful Improvements in Combined Sparking Plugs and Spark Intensifiers for Internal-Combustion Engines, of which the following is a specification, reference being had to 10 the accompanying drawings.

This invention relates to combined sparking plugs and spark intensifiers for internal combustion engines.

An important object of the invention is to 15 provide a device of this character comprising a porcelain body portion having disposed therethrough a main electrode, the ends of which project beyond the ends of the porcelain body portion, the porcelain body 20 portion having mounted upon the ends thereof ground members which are space insulated from one another and which may be interchangeably employed for engaging in the spark plug opening of the cylinder of 25 the engine, each of the ground members being provided with means for attaching thereto a lead wire connected with a suitable source of electrical supply, the lead wire in 30 operation being connected with the ground member which is remote from that engaged in the spark plug opening of the cylinder.

A further object of the invention is to provide in a device of the character above described means whereby the lead wire may 35 be connected with the ground members by means of a clip readily engageable from the members in order that the interchanging of the ends of the device may be accomplished with the least possible loss of time.

40 A still further object of the invention is to provide means normally forming a portion of the device for reinforcing the resilient body member which must of necessity be made of some length and accordingly susceptible to breakage.

Other objects and advantages of the invention will become apparent throughout the course of the following description:

In the accompanying drawings, wherein 50 for the purpose of illustration is shown a preferred embodiment of my invention, and wherein like reference characters designate like parts throughout:

Figure 1 is a longitudinally sectional view

taken through a combined spark plug and 55 intensifier constructed in accordance with my invention;

Figure 2 is a section taken on the line 2—2 of Figure 1, and

Figure 3 is an enlarged detail sectional 60 view showing the construction of the attaching plate.

Referring now more particularly to the drawings, the numeral 10 designates a body portion formed of porcelain which embodies 65 a central, enlarged portion 11 which is materially reduced at its ends, as at 12. Beyond the reduced portions 12 the porcelain 10 is enlarged, as at 13, and beyond these enlarged portions 13 is provided with further reduced portions 14.

A main electrode 15 is provided which is embedded within the porcelain 10 and has its end portions 16 reduced adjacent the upper ends of the enlarged portions 13 and 75 such reduced portions extending through the ends of the reduced portions 14 and being exposed. The heavy portion of the main electrode stiffens the body of the porcelain 10 and resists breakage thereof.

The enlargements 13 combine with the reductions 12 and 14 to form on the ends of the enlargements 13 shoulders 17 and 18 adapted to have positioned thereagainst gaskets 19 and 20 of any suitable construction. Cylinder engaging members 22 of conducting material are provided having a central bore 22^a adapted to receive therein the reduced portions 14. The bores 22^a of the members 22 are enlarged at their inner 90 ends, thereby forming shoulders 24 which abut the gaskets 19. The exteriors of the extreme end portion of the members 22 are externally screw threaded for coaction with the usual screw threaded bore formed in the internal combustion engine cylinder for the reception of the spark plug, and inwardly of the screw threaded portions the members 22 are enlarged and provided in such enlarged portions with grooves 25, the purpose 100 of which will presently appear. Inwardly of the grooves 25 the exteriors of the members 22 are provided with squared portions 26 by means of which the device may be applied to the engine cylinders. The inner 105 ends of the members 22, as at 27, are spun inwardly into the reduced portions 12 and engage against the gaskets 20 completing the

closure of any minute space which may be present intermediate the interior of the members 22 and the ends of the porcelain 10.

I provide a spring clip 28 adapted to encircle the member 22 within the groove 25. An attaching member is provided having a shoulder 29 formed thereon centrally, one end of the attaching member extending through a suitable opening formed in the clip 28 and being riveted upon the opposite side thereof, as at 30, the opposite end of the member being externally screw threaded, as at 31, for the reception of a nut 32 by means of which the lead wire 33 may be securely fastened in position.

In the operation of my device the threaded portion of one of the members 22 is engaged in the threaded opening formed in the cylinder of the engine and the other of the members 22 is electrically connected with a suitable source of electrical supply. The members 22 are each provided as at 23 with what may be described as a ground terminal which terminates adjacent to but spaced from the exposed corresponding end 16 of the main electrode 15. A current upon completion of the circuit in the usual manner will pass through the member 22, the contact 23 thereof, jump the gap to the exposed end of the electrode 23 and cause a second spark at the gap between the electrode 23 and the lower or cylinder-entering end of the main electrode 15. It will be seen that a spark is formed not only within the cylinder but that an intensifier gap is provided exteriorly of the cylinder and at such point where the spark jumping the gap will be readily visible. When it is desired to interchange the ends of the plug for any purpose, the disconnection of the terminals may be readily accomplished by a slight pull, and the reconnection thereof at the opposite end of the device may be made with

a minimum loss of time due to the peculiar construction.

Particular attention is directed to the fact that the use of but a single lead wire connection is necessary in the construction of my device, and that this lead wire may be readily detached and interchanged when desired; and attention is further directed to the fact that the construction of my device is extremely simple and accordingly, one which may be produced very cheaply, rendering the device particularly well adapted for the use for which it is intended.

It will be obvious to those familiar with the art that the construction hereinbefore set forth may be somewhat varied without in any manner departing from the spirit or scope of my invention, as for example, variations in the means of attaching and gasketing members 22 to the porcelain 10. I, accordingly, do not limit myself to the specific construction hereinbefore set forth except as so limited by the subjoined claim.

What I claim is:

A combined spark plug and spark intensifier comprising an insulatory body portion embodying a central enlargement and reduced ends, an electrode extending longitudinally of said body portion and having its ends projecting through the ends thereof, spark plug opening engaging members secured to the reduced ends of said body portion and each embodying a contact extending adjacent the adjacent end of the electrode, said electrode being provided centrally with a relatively thickened portion reinforcing the relatively thickened portion of the insulatory body portion and extending into the reduced ends thereof.

In testimony whereof I hereunto affix my signature.

CHARLES L. THAYER.
